SAML. S. BOYD.

GEO. E. CUMING.

UNITED STATES PATENT OFFICE.

GEORGE E. CUMING, OF ST. LOUIS, MISSOURI.

DESIGN FOR A SHOW-STAND.

SPECIFICATION forming part of Design No. 13,856, dated April 17, 1883.

Application filed January 15, 1883. Term of patent 7 years.

To all whom it may concern:

Be it known that I, GEORGE E. CUMING, a citizen of the United States, residing in St. Louis, Missouri, have invented and produced 5 a new and original Design for Show-Stands, of which the following is a full, clear, and exact description, reference being had to the accompanying photograph, forming part thereof.

The leading feature of this design is the figure of a human foot mounted upon a base against, around, or about which the articles to be exhibited are placed, and having an upright or back extending from the base upward in rear of the foot, and a ledge extending 15 around the base, at or near the bottom thereof.

A represents the figure of the foot. B represents the base. So far as the combination of the foot and base is concerned, the outline

of the base may be varied somewhat from the exact form shown in the photograph. C represents the upright behind the foot. D represents the ledge extending around the base. 20

I claim—

1. The design for show-stands herein shown and described, the same consisting in the foot 25 A, mounted upon the base B, and having the upright C in rear of the foot.

2. The design for show-stands herein shown and described, the same consisting in the foot A, mounted upon the base B, with the upright 30 C in rear of the foot, and the ledge D, extending around the base.

GEO. E. CUMING.
